METHOD AND APPARATUS FOR DRYING

William Hale Charch, Buffalo, N. Y., assignor, by
mesne assignments, to E. I. du Pont de Ne-
mours & Company, Wilmington, Del., a corpo-
ration of Delaware

Application October 23, 1935, Serial No. 46,325

1 Claim. (Cl. 34—48)

This invention relates to the drying of non-fibrous sheets and films which are subject to shrinkage during the drying thereof. This invention will be particularly described in relation 5 to the drying of regenerated cellulose sheeting cast from viscose and adapted to be used as a wrapping tissue.

Heretofore, in the manufacture of such sheets or films of regenerated cellulose the film was 10 cast from viscose into a coagulating and/or regenerating bath and subsequently passed through additional baths such as regenerating, desulfurizing, washing, bleaching and glycerinating baths. Thence, it was passed through a drying apparatus 15 and wound up into rolls. In passing through the said drying apparatus, the film loses moisture, and in losing this moisture tends to shrink to a great extent, thus diminishing the area of the regenerated cellulose film and tending 20 to produce pockers or wrinkles therein. In order to produce a relatively thin sheet or film of comparatively large area without pockers or wrinkles, the drying apparatus customarily consists of a series of rotating heated rolls around 25 which the film passes and which, due to the friction between the film and roll surfaces, keep it at all times under a marked tension and thus prevent or reduce shrinkage of the film.

It has now been found particularly advan- 30 tageous to employ various solutions or suspen-
sions to wet sheets or films, hereinafter to be
termed generally as webs, and particularly webs
in the gel state, for the purpose of imparting
certain, special, desirable properties thereto.
35 When certain of the above named solutions or
suspensions are applied to the web, difficulty is
encountered in the subsequent drying stage by
reason of the fact that the applied material tends
to concentrate in the web as the liquid is removed
40 until it reaches the point where it tends to stick
to the roll in whole or in part. This sticking of
the applied material to the roll surface results
in an increasing fouling of the roll surface so that
the machine must soon be shut down for clean-
45 ing. At the same time, there is a constant in-
terchange of the material on the rolls with that
in the web, some of the surface material in the
web sticking to the rolls and some of the pre-
viously deposited material on the rolls again
50 sticking to the web. When this happens, the
web has a speckled or patched appearance due
to the deposit thereon of small particles of the
applied materials, or due to the removal of small
sections of the applied material therefrom.
55 When it is realized that the ultimate product

finds its greatest utility because of its glass-clear transparency, it will be readily seen that difficulties of this kind materially interfere and in some cases forbid the successful manufacture of films to which otherwise desirable solutions and suspensions have been applied. 5

Although the present invention is applicable to non-fibrous, shrinkable sheets and films to which have been applied all types of materials which may during drying induce speckling of the 10 finished web, I am primarily concerned with the drying of the films to which certain recently developed, non-heat-plastic materials have been applied, that is to say, materials which are not flowable under the application of a reasonable 15 degree of heat, and consequently wherein there is no opportunity for removing the speckled or patched appearance therefrom.

It is therefore an object of this invention to 20 provide a method and apparatus for drying non-fibrous, transparent sheets or films which are subject to shrinkage during the drying thereof.

It is another object of this invention to 25 provide a method for drying non-fibrous, transparent sheets or films, which contain substances for imparting special characteristics to said film, without the appearance of speckles or patches thereon.

It is a more specific object of this invention 30 to provide a method and apparatus for drying a regenerated cellulose sheet or film containing a substance which may adhere to an adjacent surface during the drying thereof by passing the same over drying rolls which are provided with means for maintaining the roll surface in a dry 35 state.

Other objects of the invention will appear 40 hereinafter.

The objects of this invention can be achieved generally by passing the web into contact with 45 drying rolls which are provided with means for maintaining the same in a substantially dry state; preferably, however, the web is first preliminarily dried out of contact with any surface by an application of intense heat until a large 50 part of the liquid has been removed therefrom.

The invention will be more easily understood 55 by reference to the following detailed description taken in connection with the accompanying illustrations, and in which:

Figure 1 is a fragmentary, diagrammatic, elevational view of one form of drying apparatus suitable for use in accordance with the present invention.

Figure 2 is a fragmentary, diagrammatic, ele- 55

vational view showing a modified form of drying apparatus.

Figure 3 is a plan view on an enlarged scale taken along the line 3—3 of Figure 2.

Referring to Figure 1 of the drawings, reference numeral 10 designates a comparatively wide web of non-fibrous, cellulosic material, such as regenerated cellulose which has been cast, regenerated, desulfured, bleached, washed and glycerinated, but undried. This film is led through the liquid bath in vat 11 by passing the same over rolls 12. From rolls 12 the web is passed through squeeze rolls 13, after which it is led through a narrow opening 14 of the drying enclosure 15, which is of the type described and claimed in the copending application of Walter C. Eberlin, Serial No. 46,326 filed of even date. The web has no contact with any solid surface throughout its passage through the enclosure 15, it being supported at opposite ends thereof by the squeeze rolls 13 and supporting roll 16. A plurality of headers 18 are positioned to project from the top and bottom of the enclosure 15. These headers, instead of being directed perpendicularly against the web are preferably arranged to project forwardly at an angle in the direction of the movement of the web. A large plurality of hot air or gas jets or open flame gas burners 17 are arranged on each header and are preferably positioned to project forwardly in the same direction as the headers. The headers 18 are connected to a common chamber which is supplied with a heated gas or a combustible gas by an inlet conduit (not shown). The burners or jets are so arranged in multiple units that the whole width of the web is exposed to the hot gases or products of combustion. When burners are used, they are so spaced that sufficient passage exists between flames for an ample supply of secondary air to reach the flames and for the products of combustion to escape. The burners or jets may, if desired, be made individually adjustable so that wet bands may be eliminated from the films and the latter be dried to produce a flat sheet.

A plurality of narrow outlet openings 22 for the hot gases or products of combustion are arranged intermediate the headers. The openings 22 in the upper portion of the enclosure 15 are connected to a common chamber 24 from which the gases or combustion products are withdrawn through the conduit 28 and suction fan 32. The openings 22 in the lower portion of the enclosure 15 are connected to the chamber 26 from which they are withdrawn through conduit 30 and a suction fan (not shown).

The film passes from the enclosure 15 through the narrow opening 34, thence over the supporting roll 16 to a series of heated drying rolls 40 which may, if desired, be of the type disclosed in United States Patent No. 2,046,553 to D. H. Edwards, or the type disclosed in the United States patent application of F. P. Alles and D. H. Edwards, Serial No. 728,378, or both.

The first section of drying rolls which the web will contact is preferably confined within enclosure 46 which is provided with additional hot gas jets 42 and suction means 41 and 44 for withdrawing said gases therefrom. The hot gas jets 42 are connected to common headers 43 and supply conduit 45 (see Figure 3). The suction means 41 and 44 are connected to suction chambers 47 and 48 respectively by means of which the gases may be drawn off through conduits 49 and 50 by any appropriate means. The jets

42 are shown directing the hot gas against the section of the drying rolls 40 which are out of contact with the web 10, whereas the suction means 44 are arranged adjacent the webs which are moving over sections of the rolls 40. The hot gas jets 42 serve to keep the first section of drying rolls dry and thereby to prevent any adherence between the web and the drying rolls. After being led over the drying rolls within the enclosure 46, the film will be sufficiently dry to overcome any tendency thereof to adhere to the additional unenclosed drying rolls 40 which are provided in sufficient number to remove such remaining moisture content of the web as may be most desirable. The web is then collected on the winding shaft 50 in the conventional manner.

The web may be drawn through the drying apparatus by imparting rotation to any of the rolls 12, 13, 16 and 40 or to all of them, as is well known in the art. If desired, succeeding driven rolls may be regulated with any desired or expedient speed differential means to compensate for film shrinkage or to prevent excessive shrinkage. For example, the circumferential speed of the drying rolls may be slower than the circumferential speed of squeeze rolls 13 to allow for web shrinkage in the drying of the film as described and claimed in the co-pending application of William Hale Charch and Francis P. Alles, Serial No. 46,324 filed of even date.

The requisite heat may be supplied to enclosure 15 in a variety of ways, such as, direct heating by open gas flames, direct heating by electrically heated units arranged to heat by convection and radiation to the web, heating by hot gases supplied by the passage of air or other gas over steam coils, electrical or gas heated units, or otherwise heating by hot gases supplied by the combustion of gas, oil, coal or other fuel. The ultimate transfer of heat to the web is in all cases by convection and/or radiation since it would defeat the objects of the invention to permit the web to touch any surface which might transfer heat to it by conduction. Since it is necessary to transfer a large amount of heat to the web in a short time, it is desirable, with any method used, to cause the heated gas, air or flames to impinge against the web with good velocity, thus reducing the surface film of air or gas on the web to a minimum and in accord with well known heat transfer principles obtain a maximum rate of heat transfer. When hot air or other gas is used for drying the web, the gas impinging on the bottom surface thereof may be given sufficient velocity to support the film, and the velocity of the gas directed against the top surface of the film regulated so as to compensate for any excessive upward thrust of the first mentioned jets.

The film of regenerated cellulose leaving the wet end of the casting machine and entering the dry end is largely swollen with water and contains in excess of 300% water, (all figures based on dry cellulose) whereas the film as marketed contains less than 10% water. In its passage through the enclosure 15, the film must be dried to the point where it will no longer adhere to the drying rolls 40 and at the same time it must not be dried to the point where it will tend to pucker or wrinkle or to the point where material shrinkage will take place. When the film is led directly from the drying enclosure 15 to conventional drier rolls, the moisture content range of the web as it passes from the enclosure will be much smaller than where the film is led through the enclosure 15 to

the drying rolls against the surface of which hot gases are being directed. Slightly moist webs which will adhere to the conventional drier roll will not adhere to rolls against the surface of which hot gases are directed by reason of the fact that the roll surface in the latter case is kept dry. Therefore, the inter-position of a plurality of drier rolls against which hot air jets are directed also serves to eliminate the necessity for controlling and maintaining the moisture content of the web within a comparatively small range.

With the described arrangement it is possible to remove the surface layer of water from the web while the latter is entirely out of contact with any surface, and after the surface layer of water has been removed, but before the web has dried to the point where wrinkles or puckers are imparted thereto, or before material shrinkage has taken place the web is further dried while in contact with a smooth, solid surface without danger of sticking of the film to the roll surface. When fouling of the rolls takes place, the web surface becomes covered with specks or patches due to the deposition of material from the dirty rolls or the removal of portions of the applied material from the web. In webs to which heat plastic material has been applied, these specks or patches may be removed by further application of the heated roll surfaces, but when the applied material is non-heat-plastic, the specks or patches will be permanent and non-removable. Consequently, in the former case the web must be subjected to further comparatively expensive steps to remove the specks from the heat plastic coating, and in the latter case the web is permanently damaged and of little or no value.

Referring to the modified form of apparatus illustrated in Figure 2, the web 10 is passed from the tank 11 through the squeeze rolls 13 and thence directly over a series of drying rolls 40. The first drying rolls over which the web is led are positioned within the enclosure 46. These drying rolls are provided with means for directing hot gas against the sections thereof which are not in contact with the web in the same manner as above described with reference to Figure 1. This modified form of apparatus finds particular utility in the manufacture of webs which are coated with substances which need not be preliminarily dried in a freely suspended condition, but which may have a slight tendency to stick to the roll surfaces unless they are kept substantially dry. This apparatus may furthermore be used to advantage with the hot gas jets 42 as a sole means of heating the drier rolls 40. All of the drier rolls 40 may be provided with hot gas jets 42 to keep the same dry and hot, or a plurality of the rolls with which the films first come into contact may be provided with hot gas jets and the succeeding rolls may be conventional drier rolls as illustrated in Figure 2.

The temperature of the hot gases directed against the drier rolls, the speed of the passage of the film through the drier, and the velocity of the gases may be varied within wide limits to accomplish the objects of the present invention. Particularly desirable results may be achieved by maintaining the temperature of the said hot gases between 150° C. and 250° C., and passing said gases against said rolls with a velocity of at least 100 ft. per minute and a volume of at least 2 cu. ft. per minute with the film passing through the drier at the rate of about 125 ft. per minute. Va-

rious other factors may affect the above preferred conditions and the temperature, velocity and volume of the gases may be varied from the preferred ranges set forth above to produce material improvement in the resulting products, but it is to be understood of course in all cases that relatively high velocities, with the gas directed against the rolls, as distinguished from mere circulation of the circumambient atmosphere, are necessary to secure the desired result.

Although the present invention has been discussed with particular reference to regenerated cellulose, it is nevertheless applicable to webs made from other non-fibrous, transparent, shrinkable, cellulosic materials which are self-supporting during the drying thereof, or to non-fibrous, transparent, shrinkable, non-cellulosic sheets and films of similar nature.

Although the present invention is particularly useful in the drying of films or webs carrying non-heat-plastic compositions, other materials which may be applied to sheets and films and dried with great advantage in accordance with this invention include moistureproofing compositions, materials which will prevent the transmission of ultra-violet light, compositions which may be applied for anchoring subsequent coatings to the film, and the like.

The use of very intense heat to carry out the early stages of the drying leaves a very much smaller amount of drying for the later steps which follow the hot treatment. This makes possible the design of a much shorter drier with its attendant lower investment costs and maintenance and, more especially, with the reduction of the factors which make for non-uniformity of drying and which are of course magnified as the size and number of components of a machine are increased. The present invention permits of a very much higher drying speed for a given drier range and thus becomes important due to current competitive conditions.

This invention has the further advantage of the production of sheets having coatings thereon adapted to lend very desirable characteristics to the webs, but which would otherwise be extremely difficult, if not impossible of application with previously known apparatus and process steps.

It is to be understood that the specific embodiments of the invention illustrated and specifically described may be varied in many details of its construction within wide limits without departing from the nature and spirit of the invention, and that the invention is to be limited only as set forth in the appended claim.

I claim:—

In the method of drying a highly shrinkable, non-fibrous, transparent, cellulosic web adapted to be used as wrapping tissue, which web has been saturated with a treating liquid, the steps comprising passing said web substantially saturated with treating bath liquid through a drying zone comprising a plurality of open flames in which said web is maintained out of contact with any solid surface whereby to preliminarily dry the same, continuing the drying thereof by passing said web into contact with a drying roll, and simultaneously passing a hot gas against a section of said roll in such a quantity and velocity as to prevent adherence of the said web to said roll.

WILLIAM HALE CHARCH.
